UNITED STATES PATENT OFFICE.

GEORGE D. NOGUE, OF MOUNT VERNON, NEW YORK.

MULTICIRCUIT-CONTROLLING SWITCH.

Application filed February 28, 1921. Serial No. 446,627.

To all whom it may concern:

Be it known that I, George D. Nogue, a citizen of the United States, residing at Mount Vernon, New York, have invented a certain new and useful improvement in Multicircuit-Controlling Switches, of which the following is a full, clear, and exact description, such as will enable others skilled in the art to which it appertains to make and use the same.

This invention relates to switches of the kind that are used for controlling a plurality of electric circuits, and has for its main object to provide a multi-circuit controlling means which is so constructed that the condition of one electric circuit can be changed by actuating one governing member, the condition of a different circuit can be changed by actuating a different governing member and the condition of still another circuit can be changed by actuating both of said governing members simultaneously. I have herein illustrated my improved switch used in conjunction with a traffic directing signal for vehicles, but it will, of course, be understood that the switch is not limited to this particular use.

Figure 1 of the drawings illustrates diagrammatically a traffic directing signal for vehicles equipped with a switch constructed in accordance with my invention; and

Figures 2 and 3 are diagrammatic views, illustrating various ways of actuating the movable member of the switch that controls the circuits in which the "Ahead," "Left" and "Stop" indicators of the signal are arranged.

In Figure 1 of the drawings 1 designates an indicator that denotes the normal direction of travel of the vehicle, for example, the word Ahead, 2 designates an indicator that denotes a proposed change in the path of travel of the vehicle, for example, the word Right or an arrow or hand pointing to the right, 3 designates an indicator that denotes a proposed change in the opposite direction, for example, the word Left or an arrow or hand pointing to the left, and 4 designates an indicator provided with the words Stop or Slow. If the signal is of the type in which the indicators are rendered visible through a translucent sign plate by lighting units arranged behind the sign plate, separate and distinct lighting units 1^a, 2^a, 3^a and 4^a are provided for the indicators 1, 2, 3 and 4, respectively. The cir-

cuits in which the lighting units for the right, left and stop indicators are arranged are governed by a switch under control of the operator in charge of the vehicle and the circuit in which the lighting unit 1^a of the ahead indicator is arranged is preferably governed automatically by a means which causes the ahead indicator to be rendered inoperative automatically whenever one of the other indicators is rendered operative and to be thereafter restored to its normal operative condition whenever such other indicator is rendered inoperative or restored to its normal inoperative condition. The signal herein shown is equipped either with a single pilot light or with a plurality of pilot lights 1^b, 2^b, 3^b and 4^b consisting of small incandescent lamps, arranged in proximity to the driver in charge of the vehicle and connected in series with the lighting units of the indicators 1, 2, 3 and 4, respectively, so as to enable the operator to know at all times either that one of the indicators is operative or which one of the indicators is operative. The signal may either comprise one set of indicators arranged at the rear end of the vehicle or two separate and distinct sets of indicators arranged at the front and rear ends of the vehicle and connected in series with each other and with the pilot light or lights in proximity to the operator in charge of the vehicle.

The ahead indicator 1 is preferably controlled automatically by a relay A arranged in the common return of the controlling circuits for the right, left and stop indicators. Consequently, when either the right, left or stop indicator is rendered operative the relay A will open the circuit of the ahead indicator, and thus automatically render the ahead indicator inoperative. Thereafter, when the right, left or stop indicator, which is then operative, is restored to its normal inoperative condition the ahead indicator 1 will be automatically restored to its normal operative condition.

The controlling means for the right, left and stop indicators preferably consists of a switch governed by two buttons or other suitable elements 12 and 13 arranged in proximity to the driver, preferably attached to the steering wheel of the vehicle in such a position that said three indicators can be operated without the necessity of the driver removing his hand from the wheel or his eyes from the road ahead. By pressing the

right hand button 12 the right indicator 2 will be rendered operative, by pressing the left hand button 13 the left indicator 3 will be rendered operative, and by pressing both of the buttons 12 and 13 simultaneously the stop indicator 4 will be rendered operative. The switch governed by the buttons 12 and 13 preferably comprises a walking beam 14 that is pivotally connected midway its ends to a movable or slidable support 15, as shown in Figure 1, the buttons 12 and 13 being mounted on the opposite ends of said walking beam. The beam 14 is provided with a conducting arm 16 interposed between two contacts 17 and 18 arranged in the circuits of the right and left indicators, respectively, and the shiftable support 15 on which the walking beam 14 is pivotally mounted is provided with a conducting portion 19 that co-operates with a contact 20 arranged in the circuit of the stop indicator 4. A contractile spring 16^a is connected to the upper end of the conducting arm 16 of the walking beam so as to normally hold said arm out of engagement with the contacts 17 and 18 and also hold the conducting portion 19 on the walking beam support out of engagement with the contact 20. The beam 14 can be operated directly from the push buttons 12 and 13 at the ends of same or indirectly through a suitable means that will transmit movement to said beam from suitable controlling devices. For example, as shown in Figure 2, controlling devices 12^a and 13^a on the steering wheel of the vehicle can be associated with pneumatic or hydraulic devices 21 and 22 in such a way as to cause the beam 14 to move in a direction to close the circuit of the right indicator when the controlling device 12^a is operated, move in a direction to close the circuit of the left indicator when the device 13^a is operated, and move in a direction to close the circuit of the stop indicator when the devices 12^a and 13^a are operated simultaneously. Figure 3 illustrates another method of operating the beam 14 of the controlling switch consisting of controlling devices 12^b and 13^b on the steering wheel of the vehicle electrically connected with electro-magnets 21^b and 22^b that actuate the beam 14 in such a manner that when the controlling device 12^b is actuated the circuit of the right indicator will be closed, when the controlling device 13^b is actuated the circuit of the left indicator will be closed and when the controlling devices 12^b and 13^b are actuated simultaneously the circuit of the stop indicator will be closed.

In the various forms of my invention above referred to an electro-magnetic relay A is employed to automatically govern the operation of the ahead indicator, the windings of said magnet A being in series with

the common return of the controlling circuits for the right, left and stop indicators. When the magnet of the relay A is energized its armature is actuated, thereby opening the circuit of the ahead indicator, and thus rendering the ahead indicator inoperative. The same result can be accomplished in various other ways, however.

Having thus described my invention, what I claim as new and desire to secure by Letters Patent, is:

1. A controlling switch for three electric circuits, comprising a reciprocating support provided with a conducting portion and adapted to be moved towards and away from a stationary contact, a beam pivotally connected intermediate its ends to said support, a conducting arm on said beam arranged intermediate two stationary contacts, said beam being adapted to be rocked on its axis so as to move the conducting arm thereon into and out of engagement with the contacts between which it is interposed, and means for normally maintaining the conducting portion of said support and the conducting arm on said beam out of engagement with the contacts with which they co-operate.

2. A controlling switch for three electric circuits, comprising a reciprocating support provided with a conducting portion and adapted to be moved towards and away from a stationary contact, a beam pivotally connected intermediate its ends to said support, a conducting arm on said beam arranged intermediate two stationary contacts, said beam being adapted to be rocked on its axis so as to move the conducting arm thereon into and out of engagement with the contacts between which it is interposed, and a spring arranged to exert pressure on said support and on the conducting arm of said beam so as to normally hold said conducting arm in a neutral position with relation to its co-operating contacts and to hold the conducting portion of said support in an inoperative position with relation to its co-operating contact.

3. A controlling switch for three electric circuits, comprising a reciprocating support provided with a conducting portion and adapted to be moved towards and away from a stationary contact, a beam pivotally connected intermediate its ends to said support, a conducting arm on said beam arranged intermediate two stationary contacts, said beam being adapted to be rocked on its axis so as to move the conducting arm thereon into and out of engagement with the contacts between which it is interposed, and a contractile spring connected to the conducting arm on said beam, for the purpose described.

GEORGE D. POGUE.
